DANGER SIGN

David Hays, Milford, Conn.

Application September 2, 1949, Serial No. 113,761

1 Claim. (Cl. 40—125)

1

This invention relates to danger signs for parked automobiles and trucks, and has for an object to provide a safety device for automobiles and trucks comprising a sign which can be set up a hundred feet or so in front or back of a stopped car or truck on the road, as, for example, when making repairs or changing a tire, to warn approaching drivers, and further, to provide such a sign which can be readily detached or taken down and carried in the car and as readily set up for use.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a front view of this device set up ready for use;

Fig. 2 is an end view thereof;

Fig. 3 is a view of the back of the plate;

Figs. 4, 5, 6 and 7 are detail sections thereof substantially on lines 4—4, 5—5, 6—6 and 7—7 respectively of Fig. 3, and

Fig. 8 is a rear view of the device taken down and ready for storing in a car.

The device comprises a sign plate 10 of any suitable material, preferably sheet metal, with a danger sign 11 on it of any suitable words. The surface of the plate 10 may be a luminous or light reflecting surface forming a background for the letters, or, if preferred, the letters could be the reflecting surface contrasting with the surface of the plate. When in use it is supported on three supporting legs 12 and 13, the two legs 12 being located adjacent the ends of the plate 10 and substantially in the plane of the plate, while the leg 13 is attached to the plate at substantially the center thereof and is inclined backwardly and downwardly therefrom to provide a steady-ing and supporting brace, as shown in Fig. 2. A simple and effective means is provided for securing these legs to the plate 10. The two forward legs 12 are permanently attached to the plate, while the inclined leg 13 is detachably connected therewith. These legs are preferably substantially flat strips of metal, and the legs 12 are pivotally connected to the plate 10 by suitable rivets 14. This rivet connection permits the legs 12 to be swung laterally to lie against the back of the plate 10 when not in use, as shown in Fig. 8, and then when it is desired to set up the sign they may be easily and quickly swung to the sup-

2

porting position of Fig. 1 and the dotted line position of Fig. 3, to extend downwardly from the lower edge of the plate 10. To retain them in this position a pair of lugs 15 and 16 for each leg are lanced and bent backwardly from the plate 10 and, as shown in Figs. 3 and 4, are spaced substantially the width of the legs 12 or a little greater to provide proper clearance. The lug or ear 15 is substantially at right angles to the plate 10, while the lug or ear 16 is somewhat inclined, as shown in Fig. 4, toward the lug 15, so that in swinging the leg from the collapsed position shown in Fig. 8 and in full lines in Fig. 3, it will slide up the inclined lug 16 to the dotted position of Fig. 4, flexing the leg slightly, and then when over the space between the lugs 15 and 16 the resiliency of the material will cause it to seat between the two lugs 15 and 16 and retain it in this position when the device is in use. In collapsing or taking down the device the leg is merely sprung backwardly to remove it from the position between the lugs 15 and 16, so that it is released, and then it may be readily swung to the position lying against the back of the plate 10, as shown in full lines Figs. 3 and 8.

As above indicated, the central or bracing leg 13 is detachably connected to the plate 10. For this purpose the plate 10 is lanced longitudinally at the center thereof adjacent the top and bottom edges, and then the material between these cuts or lances is forced backwardly to form the loops 17. The leg 13 is bent at the proper angle at 18, forming the upright portion 19 which is inserted through these loops 17, and the loops are so formed as to provide a gripping action on the portion 19 of the leg to secure it to the plate 10, but will permit ready withdrawal or separation from the plate when taking down the plate, and then it may be placed on the back of the plate between the folded legs 12, as shown in Fig. 8. The parts may be placed in a suitable flat package or carton.

In use, the operator when forced to halt his car or truck on the road, may readily set up this device by swinging the two legs 12 from the folded position shown in full lines in Figs. 3 and 8 to the full line position of Fig. 1 and the dotted line position of Fig. 3, where they are securely held by the rivet 14 and the lugs 15 and 16. The leg 13 may be easily and quickly attached to the plate 10 by merely inserting the end portion 19 through the loops 17, and the device may be set at the proper distance either to the front or the rear of the halted car or truck, and will provide a very effective warning to an approaching driver. The legs form a very stable support for the sign

so that it is not liable to be blown over. After use, it may be as readily taken down and stored in the car by merely withdrawing the leg 13 from the loop 17 and then swinging the legs 12 to the back of the plate 10.

It will be noted that in this construction the plate itself is the means for connecting the supporting legs and the legs are therefore connected to the plate rather than to each other or some separate structure.

Having thus set forth the nature of my invention, I claim:

A portable warning sign comprising a metal plate forming the body of the sign provided with a warning indication visible from the front thereof, a pair of forward supporting legs adjacent the opposite ends of the plate, means for pivotally securing said legs to the plate to extend downwardly therefrom in a supporting position and foldable to a collapsed position along the back of the plate, a third leg secured to the plate at an intermediate position and inclined downward-

ly and rearwardly therefrom, said latter leg including an upper end portion bent at an angle to the inclined portion, and said plate being provided with at least one loop lanced and bent outwardly from the plane of the plate and extending longitudinally thereof in which said upper end is inserted to secure it to the plate.

DAVID HAYS.
